UNITED STATES PATENT OFFICE.

OSWALD S. PULLIAM, OF PITTSBURGH, AND JOHN ALLISON, OF DRAVOSBURG, PENNSYLVANIA, ASSIGNORS TO PITTSBURGH EQUIPMENT COMPANY, OF PITTSBURGH, PENNSYLVANIA, A CORPORATION OF PENNSYLVANIA.

SIDE-FRAME CONSTRUCTION.

1,117,518.

Specification of Letters Patent. Patented Nov. 17, 1914.

Application filed May 7, 1908. Serial No. 431,373.

To all whom it may concern:

Be it known that we, OSWALD S. PULLIAM and JOHN ALLISON, respectively of Pittsburgh and Dravosburg, in the county of Allegheny and State of Pennsylvania, have invented certain new and useful Improvements in Side-Frame Construction, of which the following is a specification.

The object of our invention is to provide a new and improved side-frame construction, and to this end our invention consists of a side-frame, in the novel features of construction, and in the combination of parts all as fully herein described and claimed.

15 In the accompanying drawings, which illustrate applications of our invention, Figure 1 is a perspective view of a side-frame proper and journal-boxes embodying our invention; Fig. 2 a part elevational and a part 20 sectional view of an end of the form of Fig. 1; Fig. 3 a perspective view of a journal-box; Fig. 4 a part side elevational and a part sectional view showing a modified form of our invention; Fig. 5 a part plan and a 25 part sectional view, the section being taken on line 5—5 of Fig. 4; Figs. 6 and 7 detail plans showing tie-bars in engagement with lugs on the lower-member of side-frame proper; Fig. 8 a part elevational and a part 30 sectional view, the section being taken on line 8—8 of Fig. 4; and Fig. 9 a perspective view of filler employed.

Referring to the drawings, and first to the form of Fig. 1, the side-frame construction 35 therein illustrated comprises the side-frame proper and the journal-boxes secured thereto. The side-frame comprises a top-member 1, a bottom-member 2, web-portions 3 connecting the top and bottom-members, a 40 spring-seat 4 and end-members or plates 5. All of the elements above mentioned, as illustrated and as preferred are made in an integral cast metal structure and the end members or plates 5 which are formed on 45 the top member of the side frame are designed to be employed for the lids or tops of the journal boxes. In this form the top and bottom-members are of channel-form and are arranged with their side flanges extending in opposite directions or toward 50 each other.

The top-member 1 has formed integral therewith, push-pockets 6, and the bottom-member is formed with lugs 7, adapted to 55 engage a tie-bar 8. The tie-bar 8 and the en-

gaging-lugs 7 are particularly shown by Figs. 6 and 7.

The side-frame is formed with a bolster-receiving-opening 9 and, as illustrated and preferred, this receiving-opening 9 is of the same width throughout its length. The width of the opening 9 is designed to be less than the width of a bolster 10 measured over its column-guides 11, as shown by Fig. 4.

12 designate journal-boxes each formed with an opening 13 therein. In the form of Fig. 1 the journal-boxes are provided with arms 14 adapted to be connected with the bottom-member of the side-frame and with an engaging-flange 15 which latter fits into a receiving-groove 16 of the plate-member 5. When the journal-boxes are secured to the ends of the side-frame the plates or members 5 extend over the upper portion of the journal-boxes and serve as tops for the boxes.

In place of having a separate journal-box wedge, this wedge, under our construction, may be formed integral with the plate-member 5. In Fig. 2, we have shown the wedge 17 as part of the said member with the wedge in contact with the brass bearing 18.

In the form of Fig. 4 we have shown our invention in connection with the bolster 10 and springs 18 in place in the bolster-receiving-opening. In this form, the journal-boxes are secured to the end of the side-frame in a different manner than that of the form of Fig. 1 and the opening 13 of the journal-box is made smaller than the opening of the first form. In this form the boxes are each formed with spaced lugs 19 adapted to engage members 20 of the side-frame and the plate-member 5 is secured to the respective boxes by bolts 21.

Attention is called to the contraction of the width of the bolster between its column-guides or to the cut-in or recessed portions into which the arms 23 of the filler fit. In this construction we show the wedge 17 separate from the plate-member 5 but with the plate-member in contact with the wedge.

22 designates a movable filler supported upon the springs 18 and having upwardly projecting arms 23 interposed between the sides of the bolster and the walls of the opening and arranged between the column-guides 11 of the bolster.

What we claim is:

1. In a side-frame construction, the com- 110

- 5 combination with a bolster having column-guides formed integral therewith, of a side-frame formed with bolster-guides and a bolster receiving opening, said column-guides being projected to engage the bolster-guides, and a filler interposed between the bolster-guide and the bolster.
- 10 2. In a side-frame construction, the combination with a bolster having column-guides formed integral therewith and a recess adjacent-to the column-guides, of a side-frame formed with bolster-guides and a bolster receiving opening, said column-guides being projected to engage the bolster-guides, and a filler located in the recess of the bolster and between the bolster-guide and bolster.
- 15 3. In a side-frame construction the combination with a bolster having column-guides formed integral therewith and a recess adjacent to the column guides of a side-frame comprising a top-member formed with a journal-box lid and a bottom-member, said frame formed with a bolster-receiving-opening of substantially the same width throughout its length and with the width of the opening less than the width of the bolster measured over its column-guides, and a filler-member located in the recess of the bolster.
- 20 4. In a side-frame construction, the combination with a bolster having column-guides formed integral therewith and with a recess on each side face, of a side-frame comprising a top-member having journal box lids formed integral therewith, a bottom member, said frame having a bolster-receiving opening of substantially the same width throughout its length and with the width of the opening less than the width of the bolster measured over its column-guides, and a filler having upwardly extending members located in the recesses of the bolster.
- 25 5. In a side-frame construction the combination with a side-frame proper formed with a bolster-receiving opening of substantially the same width throughout its length and with the width of the opening less than the width of the bolster measured over its column-guides, of a bolster located in the opening having column guides and formed with a recess on each side thereof, bolster springs, and a filler having upwardly extending members, said filler interposed between the springs and the bolster and having its upwardly extending members located in the recesses of the bolster.
- 30 6. A side-frame comprising a top-member of channel form having push-pockets formed integral therewith.
- 35 7. The combination with a journal-box open at its top and provided with an outwardly projecting-arm, of a side-frame having a top-member formed with a top for the

journal-box, a bottom-member having a spring-seat formed integral therewith, means for securing the arm of the journal-box to the bottom-member of the side-frame, and co-acting engaging-means on the top-member and journal-box.

8. In a car truck, side frames having columns, a bolster spaced away from the inner faces of said columns, column guides which coöperate with said columns, said column guides being formed integral with the bolster, and removable fillers interposed between said bolsters and columns; substantially as described.

9. In a car truck, side frames having columns, a bolster spaced away from the inner faces of said columns, column guides which coöperate with said columns, said column guides being rigidly secured to the bolster, and removable fillers interposed between said bolster and columns; substantially as described.

10. A car truck having side frames including columns, a bolster provided with column guides which coöperate with said columns, said bolster being spaced away from the inner face of the columns, and removable fillers interposed between said bolster and columns; substantially as described.

11. In a car truck, side frames having columns, a bolster spaced away from the inner faces of said columns, column guides which coöperate with said columns, said column guides being formed integral with the bolster, and removable fillers loosely mounted between said bolster and columns; substantially as described.

12. A car truck having a side frame including columns and a spring seat, a spring on said spring seat, a bolster mounted on said spring and provided with column guides which coöperate with said columns, said bolster being arranged between said columns and spaced away from the inner faces thereof, and removable fillers interposed between said bolster and columns; substantially as described.

13. In a car truck, side frames having columns and a spring seat, a bolster having pairs of column guides which coöperate with said columns, removable fillers interposed between said bolster and columns, each of said fillers being arranged between a pair of said column guides, and springs interposed between said bolster and spring seat; substantially as described.

In testimony whereof we affix our signatures in presence of two witnesses.

OSWALD S. PULLIAM.
JOHN ALLISON.
